UNITED STATES PATENT OFFICE.

SAMUEL F. LEAKE, OF PHILADELPHIA, PENNSYLVANIA.

PNEUMATIC DISPATCH-TUBE.

SPECIFICATION forming part of Letters Patent No. 431,698, dated July 8, 1890.

Application filed October 26, 1889. Serial No. 328,245. (No model.)

To all whom it may concern:

Be it known that I, SAMUEL F. LEAKE, a citizen of the United States, residing at Philadelphia, in the county of Philadelphia and 5 State of Pennsylvania, have invented certain new and useful Improvements in Pneumatic Dispatch-Tubes, of which the following is a specification.

My invention has relation to pneumatic 10 dispatch-tubes or systems of the form comprising main and branch or sub lines, and having at the junction of said lines movable tubular switches which form part of the dispatch-tubes; and it has for its object an arrangement of said switches and devices for 15 operating the switches, whereby they can be positively and expeditiously moved to cause the carriers to travel in the main line to the desired sub-station, to divert the carriers 20 from a main line to a branch line and from the latter to the former without permitting loss of the vacuum or air pressure of the system at said switches, and without necessitating the use of flexible or other sealed joints 25 for the switches.

My invention has for its further object to provide mechanical devices for quickly setting the switches, which mechanical devices are actuated by the vacuum or air pressure 30 of the system under the control of electrical appliances located at the switch or sub-stations.

My invention has for its further object a tubular form of dispatch-tube having rails 35 therein and carriers having end wheels for travel on said rails to diminish the frictional contact between the tube and carriers.

My invention accordingly consists of the combinations, constructions, and arrangements of parts as hereinafter described in the specification, and pointed out in the claims, reference being had to the accompanying drawings, wherein—

Figure 1 is a sectional plan of part of a 45 main line and a sub-station line with oscillating switches therefor, and part of the mechanical devices for the switches embodying my improvements and showing the switches set for travel of the carriers through the main line tube. Fig. 2 is a section on the line 1 1, and Fig. 3 is a like view on line 2 2, Fig. 1. Fig. 4 is a sectional longitudinal elevation of

Fig. 1, partly broken away, showing the actuating mechanism for the switches and the electrical devices for controlling the operation 55 of the said actuating mechanism with the switches set, as shown in Fig. 1. Fig. 5 is a section on line 3 3, and Fig. 6 is a section on line 4 4, Fig. 4. Fig. 7 is a view similar to Fig. 1, showing the switches set to divert the 60 carrier from a sub-station to the main line, or reversely. Fig. 8 is a section on line 5 5, and Fig. 9 is a section on line 6 6, Fig. 7. Fig. 10 is a view similar to Fig. 4, showing position 65 of actuating mechanism for the switches and electrical devices when switches are set, as shown in Fig. 7. Fig. 11 is a section on line 7 7, and Fig. 12 a section on line 8 8, Fig. 10. Fig. 13 is a view similar to Fig. 1, showing the switches set to divert the carrier from the 70 main line into the sub-station, or reversely. Fig. 14 is a section on the line 9 9, and Fig. 15 a section on the line 10 10, Fig. 13. Fig. 16 is a view similar to Fig. 4, showing position 75 of actuating mechanism for the switches and electrical devices when the switches are set, as shown in Fig. 13. Fig. 17 is a section on the line 11 11, and Fig. 18 a section on line 12 12, Fig. 16. Fig. 19 is a sectional plan similar to Fig. 1, showing sliding switches with actuating mechanism removed. Fig. 20 is a section on line 13 13, Fig. 21 a section on line 14 14, and Fig. 22 a section on line 15 15, of Fig. 19, and showing 80 part of the actuating mechanism for the switches which are set for the main tube. Fig. 23 is a view similar to Fig. 19, showing part of the actuating mechanism therefor and the switches set to join the main line and sub-station tubes or one of its branches. Fig. 24 is a section on line 16 16, Fig. 25 a section on 85 line 17 17, and Fig. 26 a section on line 18 18, of Fig. 23, with part of actuating mechanism for said switches. Fig. 27 is a view similar to Fig. 19, showing switches set to join the sub-station branch with the main line. Fig. 90 28 is a section on line 19 19, Fig. 29 a section on line 20 20, and Fig. 30 a section on line 21 21, of Fig. 27, with part of actuating mechanism for the switches. Fig. 31 is a sectional plan of part of main line, sub-station branch, 95 and sliding switches therefor, showing a modification of actuating mechanism for the switches, and the latter set for the main line. Fig. 32 is a like view showing the switches 100

set for joining the main line and the sub-station branch. Figs. 33 and 34 are elevations of a modification of actuating mechanism shown in Figs. 31 and 32, and illustrating the 5 movable parts of the same in two positions. Fig. 35 is a longitudinal section of part of a dispatch-tube and an elevation of a carrier, showing sunken or depressed rails or tracks in tube above and below the carrier for said 10 wheels of the latter. Fig. 36 is a cross-section of tube and end wheel of carrier o . Fig. 37 is a view similar to Fig. 35, showing but one sunken or depressed rail or track. Fig. 15 38 is a cross-section of tube and carrier-wheel shown in Fig. 37. Fig. 39 is a view similar to Fig. 35, with raised tracks or rails above and below the carrier. Fig. 40 is a cross-section of same and carrier-wheel. Fig. 41 is a view similar to Fig. 39, showing but 20 one raised track; and Fig. 42 is a cross-section of same and carrier-wheel.

A represents a main-line tube, and B one of the sub line or station tubes.

As the construction and arrangements of 25 parts for joining the sub-station tube to the main tube are the same at all the sub stations or lines, a description of one answers for all.

At each sub station or line in the line of 30 the main tube A, and at a suitable distance apart, are air-tight boxes C and C', in which tube A is broken or cut away, leaving ends a projecting slightly into said boxes. Intermediate of boxes C C' and at a suitable location 35 is another like box C², into which the projecting end b of sub-station tube B leads. (See Fig. 1.) The boxes C C² are joined by a curved tube B', and the boxes C² and C' by a curved tube B², which tubes B' and B² are inlet and outlet tubes for the sub-station tube B. The tube B' has projecting ends b' and b^2 in 40 the boxes C and C², respectively, and the tube B² has like ends b^3 b^4 in the boxes C² C', respectively. The ends b^2 b^3 of the tubes B' B² are separated from each other in box C², as 45 are the end b' and the adjacent end a of tube A in box C, and corresponding ends b^4 and a of tubes B² and A in box C'. In box C² are two curved switches D and D', curving in 50 opposite directions, as more plainly shown in Fig. 3, to join the tube B to either its inlet or outlet tube. These switches are secured to an arm d , mounted upon a shaft d' , (see more plainly Fig. 2,) having suitable bearings d^2 in box C², and projecting from the latter through a sleeve d^3 , if desired, and terminating 55 in a casing E, within which the shaft d' is provided with a bevel-wheel d^4 and weighted lever or arm d^5 . In box C are two tubular 60 switches F and F', the former being straight to join the ends of the main tube A in said box, and the latter is curved to join the main tube with the sub-station tube B'. These 65 switches F F' are suitably secured to an arm f , (see more plainly Fig. 5,) mounted upon a shaft G, which is run through the box C into and through casing E and into box C', hav-

ing suitable bearings g in boxes C and C'. If desired, the exposed portions of the shaft G may run through sleeves g' . Within cas- 70 ing E the shaft G is provided with a bevel-wheel g^2 , which gears with the like wheel d^4 on shaft d' . In box C' are two tubular switches H and H', the former being straight to join the ends of the main tube A in said box, and the latter is curved to join the main tube with the sub-station tube B². These switches H and H' are suitably secured to an arm h , mounted on the shaft G. (See more plainly Fig. 6.) The boxes C, C', and C², as well as 75 the casing E, are constructed as desired, and preferably have removable covers, so that access can readily be obtained to their contained mechanism or parts. The weighted arm d^5 has a link-connection i passing through a 80 stuffing-box i' on the top of the casing E, with a cross-head i^2 , one end of which is secured to a piston-rod k of cylinder K and the other end of which passes into an elongated slotted end k' at the lower end of a piston-rod k^2 of cylinder K'. (Seen more plainly at x, Fig. 4.) The cylinders K K' are of different lengths to have different strokes, the cylinder K having the longer stroke, and both are provided with the usual valve or valves for admitting 85 to them the vacuum or air pressure or other motive power used in the system for actuating the same. The cylinders K K' of each sub-station are suitably connected by pipes and ways l and l' to the motive-power appliances. The valves of the cylinders K K' are provided with actuating-levers l^2 and l^3 , suitably mounted as desired, each of which levers carries an armature for the respective magnets l^4 and l^5 , included in a divided or other 90 suitably arranged battery or other electric circuit l^6 l^7 , which also includes a switch l^8 , having fixed terminals l^9 l^{10} and a switch-lever l^{11} . In the drawings, the motive-power appliances are shown as consisting of a vacuum-pump 95 M and reservoir L, for creating a vacuum in the system. As shown, they are located at a sub-station, and said reservoir is represented as connected by a pipe m with the box C; but in practice said pump and reservoir will 100 be located as desired, or a vacuum device at one end of the system and an air-pressure at the other end may be used, as is well known. The main and sub station tubes are provided with carrier transmitting and receiving 105 devices of any suitable kind, which are not shown in the drawings, as they are well known.

The normal position of the tubular switches in the boxes C, C', and C² are as shown in Fig. 1—that is to say, the switches F and H are set to complete the passage through the main tube A, so that a carrier will travel therein in either direction from end to end of the same, or otherwise, as desired, while the switches F', H', and D D' are out of connection or unset with any of the main or sub station tubes.

When the tubular switches in the boxes C, C', and C² are in their normal position, as de-

scribed, the electrical switch-lever l^0 at each sub-station is in contact with the fixed switch-terminal l^8 , to open the divided battery-circuits l^5 l^6 . To send a carrier from a sub-station in the direction of arrow z , Fig. 7, the switch-lever l^0 thereat is moved by the sub-station attendant into contact with the fixed terminals l^7 l^8 , as indicated in Fig. 10, to close the battery-circuit l^5 l^6 , through magnet l^3 , which then actuates its armature-lever l^2 to open the valve of the cylinder K to the vacuum in reservoir L , which draws up the piston in cylinder K , together with its piston-rod k and cross-head i^2 to raise link i and weighted lever or arm d^5 to its greater movement or highest position, and in so doing the lever d^5 rotates shafts G and d' to simultaneously oscillate all the tubular switches in boxes C , C' , and C^2 to the position shown in Fig. 7—that is to say, the switch H' in box C' is joined to the sub-station tube B^2 , and the main tube A and the switch D' in box C^2 is joined to pipes B^2 and B , to admit of the carriers passing out of the sub-station into the main tube in the direction of said arrow z , while all the other switches at said sub-station in the boxes C , C' , and C^2 are unset or out of line with the sub-station and main tubes. If the carrier is moving in the direction opposite to that indicated by the arrow z , then it will be diverted into the sub-station.

To divert a carrier when moving in the main tube A in the direction of arrow z , Fig. 7, from the main tube into the sub-station through the pipe B' , the switch-lever l^0 is closed upon the fixed terminals l^8 l^9 to close the battery-circuit through the magnet l^4 , (see Fig. 16,) to actuate its armature-lever l^3 to open the valve of cylinder K' , whereupon its piston and rod k^2 are subject to and raised by the vacuum in reservoir L to lift the cross-head i^2 and link i to oscillate weighted lever or arm d^5 , its lesser extent of movement, as indicated in Fig. 16, and in turn to rotate the shafts G and d' to move the tubular switches D and F' into connection with the main and sub station tubes A , B' , and B , as illustrated in Fig. 13, and the carrier passes from the main tube to the sub-station. If the carrier is sent out from the sub-station when the switches are set, as last described, it travels through the tube A in the direction of the arrow z' , Fig. 13.

The difference in extent of movement of the piston-rods k k^2 and of the cross-head i^2 are compensated for or allowable, as above described, by reason of one of the ends of the cross-head i^2 working in the slot k' on piston-rod k^2 .

From the foregoing it will be noted that the opening of the valves for the cylinders K K' is electrically controlled at the sub or some other stations, and that the vacuum or air pressure in the system or reservoir L controls the movement of the tubular switches in the boxes C , C' , and C^2 to set any pair of said

switches as desired for sending the carriers along the main tube A , or for diverting them from the main tube A to a sub-station, or for sending them from the latter to the former in either direction. It will also be noted that when the said tubular switches are set they remain set until the electrical switch-lever l^0 is moved into contact with the terminal l^8 to open the battery-circuit l^5 l^6 , whereupon either of the magnets l^3 l^4 ceases to attract its armature, and it returns to its normal position by gravity or spring-pressure to close the valve in cylinder K or K' . The piston of the latter then drops or falls, which movement is induced by the weighted lever or arm d^5 to oscillate shafts G and d' to return the tubular switches in boxes C C' C^2 to normal position, as indicated in Fig. 1, so that the carrier is always free to travel through the main tube to any sub-station. It will be still further noted that all the tubular switches in the boxes C C' C^2 are simultaneously moved, and that by using a pair of switches in each box, and the latter being air-tight and open to the vacuum or air pressure of the system, no flexible or other like joints are required for the switches, and all escape of air or vacuum pressure from said boxes and consequently from the system at the switches is avoided.

By arranging the main and branch or sub-station tubes with the tubular switches, as described, a single line of tubing only need be used for sending the carriers in either direction from sub-station to sub-station and from the end or main stations, and from the latter to the sub-stations, or reversely. In all cases all that is required to be done is to properly set the switches to obtain the desired path of travel.

To set the switches at the sub-stations along the line, the attendants thereat are properly notified, either from a main or other station or stations, by suitable telegraphic or other signaling, the devices wherefor are not shown in the drawings, as they are well-known and any kind may be used; I have, however, illustrated a form of the same in another pending application filed by me of an even date here-with, Serial No. 328,246, and the same are therein claimed.

Instead of using the air or vacuum pressure cylinders K K' , and electrical appliances for controlling the operation of the same, they may be dispensed with and a hand-lever m^x , in engagement with the cross-head i , be substituted, in which case a radial arm m' , with openings m^2 for a locking-pin passing through a registering-opening in lever m^x , is used to lock the latter, and in turn the tubular switches in their adjusted positions.

In Figs. 19 to 30, inclusive, the tubular switches in the boxes C C' C^2 are mounted upon sliding cross-heads or connecting-bars n , having a depending slotted arm n' , which has a link-connection n^3 with the shafts G and d' , as required, to slide the switches instead of oscillating them, the various positions of the switches and said operating mechanism

being indicated in said last-named figures. In all other respects said switches are actuated in any of the ways hereinbefore described. So, too, in using said sliding switches, the 5 shafts G and d' , with the mechanism interposed between them and the cylinders K K', as well as the separate single-acting cylinders K K', may be dispensed with, and in lieu of which said switches are connected directly to 10 the piston-rod of a double-acting cylinder K³ as indicated in Figs. 31 and 32, which show a pair of tubular switches in two different positions, to join the main line, and the latter with the sub-station branch B', respectively. In 15 this case the magnets $l^3 l^4$ are shown as acting directly upon the cylinder-valves. In Figs. 33 and 34 the magnets $l^3 l^4$ are in the form of solenoids, and their common core is shown passing into the valve-chest of the cylinder 20 K³, in which case the valve for the cylinder K³ is preferably a slide-valve like that usually employed for steam-engines. Said Figs. 33 and 34 represent the core for the solenoids in the two different positions to admit the air 25 or vacuum pressure at each end of the cylinder.

The dispatch-tubes may be of any suitable form in cross-section, and the carriers R are correspondingly configured to fit the bore 30 of the tubes or otherwise, as desired. I prefer, however, to insert or form tracks or rails P in the tubes and provide the carriers R with end wheels r, which travel on said tracks P, to diminish the friction between the carrier 35 and the tubes. In Figs. 35 and 36 I have shown the rails P depressed below the bore of the tubes, and said rails are located one on each side or at the top and bottom of the tubes. In Figs. 37 and 38 only one, or a bottom-depressed rail is shown. In Figs. 39 and 40 the rails P are illustrated as projecting beyond the bore of the tubes, and the peripheries of the carrier-wheels r are grooved to engage with said rails. In Figs. 41 and 42 45 only one projecting rail is shown.

As the various novel constructions and arrangements of parts constituting my invention may be greatly varied without departing from the spirit thereof, I do not limit myself 50 to the same as shown and described. Neither do I limit myself to any particular arrangement of the various boxes C, C', and C² and their contained tubular switches, as it is obvious that the same will be differently arranged, according to their location in the system and the number of main and sub station 55 lines or tubes leading thereto, as well as to the disposition of the latter, my invention comprising, broadly, so far as it relates to the 60 tubular switches, of the employment of the same either singly, in pairs, or in other desired numbers, which are bodily moved from end to end the same distance in the same plane as that of the tubes, in contradistinction to said switches being pivoted either at one 65 of their ends or at or near their center and

moving differently from their pivotal point to their ends.

Where the sub-station tube B is provided with the two branch tubes B' and B² all the 70 various switches and boxes C, C', and C² will be used; but when only one branch tube is used for a sub-station then only the one pair of switches F F' and box C are needed. It is also obvious that the actuating devices for 75 the tubular switches may be applied to the usual forms of switches; or, in other words, the switches are positively moved to set them, and they automatically return to their normal position, so that the carriers in any case do 80 not act to either set the switches or effect their return to their normal position. In using the motive power for actuating the switches each switch or sub-station may be provided with separate power-generating devices independent of those for operating the system, and when the double-acting cylinders are used, as shown in Figs. 31 and 32, the switches are set and unset by the motive power used; or, in other words, gravity devices are not 85 then employed to effect the return of the switches to their normal position.

The switches herein described working or moving in air-tight boxes, it will be noticed, do not and need not have close or contact 95 joints with the ends of the tubes entering said boxes, and when shifted do not uncover said tube ends to the external atmosphere, and the same are therefore to be contradistinguished from those forms of switches which are not 100 inclosed in air-tight boxes and have close, contact, or packed joints with the tube ends or their connecting plates or flanges, which tube ends are more or less uncovered to the external air when the switches are shifted or 105 moved.

What I claim is—

1. In a pneumatic dispatch-tube system, the combination of two differently-leading lines of tubes cut or broken away at their junctions, air-tight boxes at said junctions connecting said tubes, a pair of tubular switches on said boxes and forming part of said lines when moved to join the same, and actuating mechanism for moving said switches, substantially as set forth.

2. In a pneumatic dispatch-tube system, the combination of a main tube and a branch tube broken or cut away at their junctions, air-tight boxes at said junctions, a pair of 120 tubular switches in said boxes and forming part of said tubes when moved into line therewith, support for said switches, and actuating mechanism for simultaneously moving all the switches in said boxes to join one or more of 125 the switches to and disconnect the other switches from said tubes, substantially as set forth.

3. In combination with a broken or cut junction, of main and branch tubes of a pneumatic dispatch-tube system, an air-tight box 130 at said junction, a pair of movable tubular

switches in said box, a support for said switches, and actuating mechanism for moving the switches the same lateral distance from end to end to join said tubes, substantially as set forth.

4. In a pneumatic dispatch-tube system, the combination of pipe or tube B, the air-tight box C², diverging tubes B' B² from box C², a pair of differently-curved tubular switches in box C², and actuating mechanism for said switches, substantially as set forth.

5. In a pneumatic dispatch-tube system, the combination of a single pipe or tube B, diverging tubes B' B², carrier-diverting switch having two differently-curved members between said tubes B and B' B², and actuating devices for said switch, substantially as set forth.

6. In a pneumatic dispatch-tube system, carrier-diverting switches on air-tight boxes, combined with mechanism operated by the motive power in the system for actuating said switches, substantially as set forth.

7. In a pneumatic dispatch-tube system, the combination of carrier-diverting switches in air-tight boxes, mechanism operated by the motive power of the system for actuating said switches, and devices for controlling the operation of said motive power, substantially as set forth.

8. In a pneumatic dispatch-tube system, the combination of a carrier-diverting switch, mechanism operated by the motive power of the system for setting said switch and locking it in its set position, and devices for automatically returning the switch to its normal position, substantially as set forth.

9. In a pneumatic dispatch-tube system, a carrier-diverting switch, combined with mechanism actuated by the motive power of the system for actuating said switch, and electrical devices for controlling the operation of said motive power and locking the switch in its set position, and gravity devices for returning the switch to its normal position, substantially as set forth.

10. The combination of a main line A, having air-tight boxes C C', the branch line B, having air-tight box C², diverging tubes B' B², connecting-boxes C², C, and C', a pair of tubular switches in each of said air-tight boxes, and actuating mechanism in engagement with all of said switches for simultaneously moving all of the switches to change the course of the carrier through said lines and tubes, substantially as set forth.

11. In a pneumatic dispatch-tube system, the combination of carrier-diverting switches in air-tight boxes, mechanism under the control of an attendant for positively setting the switch, locking mechanism for retaining the switch in its set position, and devices for automatically returning the switch to its normal position when its locking mechanism is released, substantially as set forth. 60 65

12. In a pneumatic dispatch-tube system, the combination of a main line, a sub-line, two differently-directed branches from the sub to the main line, and carrier-diverting switches in air-tight boxes at the junction of the main line and said branches for diverting carriers from the sub-line into the main line and from the latter to the former in different directions, substantially as set forth. 70

13. In a pneumatic dispatch-tube system, the combination of separate pairs of carrier-diverting switches in air-tight boxes, movable supports for the switches, mechanism connecting said supports, and actuating mechanism for said supports for moving all the switches simultaneously, substantially as set forth. 75 80

14. In a pneumatic dispatch-tube system, the combination of air-tight boxes C C' C², switches in said boxes, a power-acting cylinder or cylinders having valves, electrical devices for controlling the opening and closing of said valves for setting the switches, substantially as set forth. 85

15. In a pneumatic dispatch-tube system, the combination of a single main line A, having air-tight boxes C C', carrier-diverting switches in said boxes, sub-line B having air-tight box C², carrier-diverting switches in box C², branches B' B², connecting box C² with boxes C C', and actuating mechanism for said switches, substantially as set forth. 90 95

16. In a pneumatic dispatch-tube system, the combination of the carrier-diverting switches in air-tight boxes, a power-acting cylinder or cylinders in engagement with the switches, and actuating devices for controlling the operation of the cylinders for moving the switches, substantially as set forth. 100

In testimony whereof I affix my signature in presence of two witnesses. 105
